UNITED STATES PATENT OFFICE.

ERNST F. ZARBOCK, OF CENTRALIA, ILLINOIS.

HYDROCARBON-BURNER.

1,060,305.

Specification of Letters Patent. Patented Apr. 29, 1913.

Application filed June 21, 1912. Serial No. 705,116.

To all whom it may concern:

Be it known that I, ERNST F. ZARBOCK, a citizen of the United States, residing at Centralia, in the county of Marion and State 5 of Illinois, have invented certain new and useful Improvements in Hydrocarbon-Burners, of which the following is a specification.

The present invention relates to improvements in hydrocarbon burners of the retort 10 type, and is designed to simplify the construction of burners of this character, and at the same time increase the efficiency and durability of these devices.

The burner is adapted for use in connection 15 with a stove or furnace, and is intended to be located in the fire chamber of the stove, for heating purposes.

The invention consists in certain novel features of construction and combinations 20 and arrangements of parts as will be herein-after pointed out, and more clearly set forth in the claims.

In the accompanying drawings I have illustrated one example of the physical embodiment of my invention constructed according to the best mode I have so far devised for the practical application of the principles of the invention.

Figure 1 is a vertical central sectional 30 view of a hydrocarbon burner, embodying the novel features of my invention. Fig. 2 is a horizontal sectional view on line 2, 2, looking down. Fig. 3 is a horizontal sectional view on line 3—3 looking up. Fig. 4 is a detail view of a modified form of oil 35 supply pipe arrangement.

In the preferred embodiment of my invention, the burner is inclosed within a retort which comprises the two sections 1 and 40 2 forming a spherical chamber, with the upper or dome section of the retort overlapping the lower section as at 3, and forming a closed joint. The fuel inlet pipe 4 is illustrated as entering centrally of the dome 45 section 1, and the end 5 of the pipe is open inside the retort. At its lower end the retort is closed by the dished bottom 6 which is provided with edge or peripheral flange 7 to receive the open lower end of the retort 50 section 2.

The retort is supported from the base plate 8 by means of posts (three being here illustrated) as 9 which are integral with the base plate, and project into complementary 55 sockets 10 in the under side of the retort-

bottom plate. In this manner the burner may be supported in the stove or furnace from the base plate. An open threaded boss 11 is formed centrally of the base plate 8, and into this boss is screwed the lower section 12 of an air inlet pipe, the upper section 13 of the pipe being seated in the upper end of the lower section as shown. The bottom-plate 6 is perforated at 14 to accommodate the air pipe, and it will be seen in Fig. 1 that sufficient space is provided at the perforation 14 for the passage of gases.

A conical cap 15 is located within the retort just below the open end 5 of the inlet pipe. This cap is supported upon cleats 16. At its perimeter the cap is fluted as at 19 and its conical face is formed with flutes or corrugations 20 which form channels extending from the apex of the cap to its fluted perimeter.

Suspended from the air pipe 13 by lugs 17 is a tapered vessel 22 which surrounds the air tube 13 and a portion of the lower section 12, and this tapered vessel or tube, which, at its upper end, is slightly less in diameter than the greatest diameter of the cap 15, tapers in diameter so that a restricted space 23 is formed between the end of the tube and the air pipe. The tube 22 is formed with a series of circumferential shoulders or 85 offsets 24.

The mode of operating the burner is as follows: The complete device as shown, is inclosed within the fire chamber of a stove or furnace and fuel oil is fed through pipe 4. When the oil reaches the fluted openings at the edge of the burner cap, the fuel in the crude oil is burned and gases formed in the retort. The gases pass downward to the opening 14, and the air, which is flowing up through the air pipe and down between said pipe and the vessel 22, mixes with these gases, the result being that the gases at their point of commingling are ignited as they pass through the opening 14 from the flame 95 which envelops the tapered vessel 22. The ignited gases follow the path indicated by the arrows out through the opening 14 under and around the retort, and the retort is heated to a red-hot condition. This heated condition of the retort converts the lighter products of crude oil into gas very quickly 100 so that it may be mixed with the inflowing air for combustion. The tapered vessel 22 because of the offsets 24 prevents the ac- 110

cumulation of products of combustion of the oil, but allows the products to drip from the offsets and finally run off from the dished bottom of the retort, through the opening 14 and onto the base plate 8. A natural draft for air through the air pipe is provided as shown by the arrows, and the gases are thoroughly commingled at the point of ignition or perforation 14.

10 In Fig. 4 I have illustrated a modified structure wherein the oil pipe 4' enters upwardly through the air pipes and pierces through the apex of the cone 15', so that the inflowing oil may spread over the cap 15', 15 as in the form shown in Fig. 1.

What I claim is:—

1. The combination in a hydrocarbon burner with an inclosing retort having a centrally perforated bottom and a fuel pipe 20 opening into the retort, of an air pipe extending into the retort, a tube encircling said air pipe, and a burner cap extending over the open ends of said air pipe and tube and

located between said members and the inlet fuel pipe.

2. The combination in a hydrocarbon burner with an inclosing retort having a perforated bottom and a fuel pipe, of an air pipe extending into the retort, a tapering tube formed with annular offsets and enclosing 25 30 said air pipe, and a burner cap extending over the open ends of said air pipe and tube.

3. The combination in a hydrocarbon burner with an inclosing retort having a perforated bottom and inlet pipe for fuel, of an air pipe, a tapering tube enclosing 35 40 said air pipe, and a conical burner cap having a fluted edge extending beyond the open ends of said tube and pipe.

In testimony whereof I affix my signature in presence of two witnesses.

ERNST F. ZARBOCK.
